FASTENING DEVICE FOR FLAT ARTICLES

Elmar Lukacs, Berlin-Schöneberg, Germany, assignor to Hinz Fabrik G. m. b. H., Berlin-Mariendorf, a corporation of Germany

Application October 25, 1927, Serial No. 228,604
In Germany June 1, 1927

6 Claims. (Cl. 129—16.8)

My invention relates to a rider clip or tab for flat articles, such as sheets, plates, cards of paper, pasteboard, metal or any other suitable material as used for books, card indexes, registers and any 5 other purposes. The rider clip or tab may serve for joining the flat articles or carrier or as clip, rider clip or marking clip. It may hold special index marks, such as plates or labels, on the flat articles or mark the flat articles. It may also 10 be used for distinguishing files, portfolios and the like in the manner of tabs bearing suitable inscriptions or numbers.

The object of my invention is to provide a particularly favorable or improved construction 15 or design of such a rider clip or tab, which ensures an extraordinarily firm seat or grip upon the flat article and is at the same time easily detachable without the aid of any appliances and which thus joins, holds or marks the flat articles 20 such as the leaves or cards of a register, card index or a book.

According to my invention the tab which is adapted to be applied to the edge of the flat article such as the edge of an index or register 25 card, comprises two oppositely arranged flat plates of sheet material fastened together along a fixed axis to form opposed limbs, at least one 30 of said limbs being constructed of resilient material to adapt it to exert a yieldable pressure upon a card or other flat article having one edge 35 disposed between it and the other of said limbs, one limb being shorter than the other limb and provided with one or more projections adapted to cooperate with said longer limb for embracing 40 the interposed card or other flat article under yieldable pressure.

On a preferred embodiment of my invention, the shorter limb is constructed of relatively stiff material and the longer limb of relatively resilient material.

According to another preferred embodiment of the invention, an edge of the shorter limb parallel to and distant from the fixed axis along which the flat plates are fastened together, is bent 45 towards the longer limb while said longer limb is provided with a transverse recess for receiving the bent edge of the shorter limb.

In the drawings affixed to my specification and forming part thereof a number of embodiments 50 of my invention are illustrated diagrammatically by way of example.

In the drawings

Figure 1 is a top plan view of one embodiment of my invention.

Figure 2 is a bottom plan view of the same.

Figure 3 is a cross-section of the same.

Figure 4 is a top plan view of the rider clip shown in Figures 1, 2, and 3 mounted upon a card.

Figure 5 is a cross-section of the same.

Figure 6 is a similar cross-section of a modified form of the rider clip shown in Figures 4 and 5.

Figure 7 is a side elevational view of another modified form of the rider clip;

Figure 8 is a top plan view of the rider clip shown in Figure 7;

Figure 9 is a top plan view of a double or twin clip embodiment of my invention.

Figure 10 is a side elevation of another modified form of the rider clip shown in Figures 4 and 5.

Figure 11 is a top plan view of another embodiment of the double or twin clip form of my invention.

Figure 12 is a side elevation of Figure 11.

The clip or tab may be bent or otherwise shaped or formed as the Figures 1 to 9 show from two sheets 11, 12 riveted together at about their middle at 13, 14 or united in any other suitable manner or it may be formed from a single sheet of material such as shown e. g. in Figure 10.

In either case, the rivets 13 and 14 determine an axis between two oppositely-presented wings, one of said wings comprising two oppositely-arranged limbs 23 and 24 which are adapted to clasp the edge of a flat article inserted between them. When the clip or tab is employed as rider mounted upon a card of a card index it may itself act as marker or indicator by the shape and configuration or the color of its vane. It may also be adapted to receive and hold indicator cards, strips, tickets or labels 17 visible through front windows 18 and, if desired, also through windows 19, 20^a in the back. The rear limb of the clip is longer than the front one and is provided about midway of its length with suitable perforations 20 which are adapted to cooperate with suitable projections 21 in the form of tongues, teeth, prongs, claws or the like of the shorter front limb, said projections being equally spaced along the edge of the shorter limb.

Fig. 4 of the drawings illustrates how such a clip is mounted as a rider upon the edge of a register card 15. This card is provided close to its upper edge with preferably equally spaced perforations 22 through which the tongues or projections 21 of the shorter limb penetrate, as particularly clearly shown in Fig. 5 of the drawings. If these tongues and the like are made narrow or slender, as shown in the drawings, the perforations in the edge of the card may be made correspondingly small so that the material of the

card is saved and the card is not substantially weakened. These projections of the shorter limb of the device which engage the longer limb at corresponding points thus ensure an extraordinarily firm seat of the rider upon the edge of the card. By bending the rider which preferably is provided with at least one elastic limb, the projections move out of the openings of the other limb as well as out of the openings of the card, so that the clip may easily be detached from the edge of the card. The longer limb at the back which on the one hand safeguards the position of the prong entering it, protects on the other hand the edge of the card against bending so that in spite of the firm seat of the rider the card is hardly exposed to any wear and tear. Since the riding clip is, so to say, also closed at the lower edge adjacent cards are prevented from slipping underneath it.

If the projections of the rider and the perforations of the card are equally spaced, the rider clip may easily be moved along the edge of the card and fixed in any position. The openings in the longer rear limb are preferably chosen slightly larger than the projections entering them. They may be circular, as shown in the drawings, or have any other shape, for instance rectangular shape.

It is not absolutely necessary that the card should have perforations through which the tongues or prongs of the one limb of the clip penetrate. If the clip is made of sufficiently strong material the projection 21 forces or displaces the material of the card towards or into the opening 20 in the back leg, as shown in Fig. 6 of the drawings, so that hereby also is secured a firm seat of the clip upon the edge of the card. The longer limb of the clip may also be made without perforations 20 and be provided with a simple depression or recess into which enters the edge of the other limb of the rider clip.

A construction of this kind is illustrated in Figs. 7 and 8 of the drawings. Here the lower edge 25 of the shorter limb of the clip is for the larger part of its width or for its entire width bent towards the other limb and engages a recess or groove 26 of the other longer limb of the rider clip.

As shown in Figure 10, the rider clips may be made by folding as at 116 one flat piece, for instance of an elastic material, which by punching or in any other suitable manner may be provided with projections 121, and openings 120 or the like along the forward edge of piece 123. The limbs 111 and 112 may be riveted together at 114.

A particularly favorable method of manufacture results from a further development of the invention for this and other rider clips of any description, if the rider clip is composed of two separate portions, that part or limb which is constructed by transforming a plate body by, for instance, producing projections upon it, being made of an unelastic material, such as open hearth steel (Siemens Martin steel), the other part or limb, which consists of a plate not machined at all or to a slight extent only, for instance merely provided with windows, being made of tool steel, and thus forming the elastic leg of the clip.

In this way the process of manufacture is greatly cheapened in so far as the very inconvenient and expensive tempering of those thin-walled bodies is rendered unnecessary, and furthermore the shaped portions of the first-mentioned limb offer such a high resistance to any

deformation that the teeth, for instance, become neither worn nor bent even when the clip is frequently handled.

The above described arrangement according to which the rider engages with inwardly directed projections, or the like of the shorter limb correspondingly shaped recesses, depressions, perforations and the like at about the middle of the length of the other limb, presents a further advantage in particular in combination with the above described process of manufacture according to which the limb formed by machining a plate is constructed of a rigid material and the other limb of an elastic resilient material.

The shorter limb may be located on the front of the card. The rider clip employed as mark or indicator then ensures a firm seating even with a short front limb, which is safeguarded by the longer back limb as well as the engagement of the front limb into the back limb.

The firmness of the seating is increased if the front limb is constructed of a rigid non-resilient material because the spreading apart of the two limbs, by bending the clip around the edge of the card is effectively prevented in spite of the shortness of the front limb. If the rider clip serves as a marker or indicating rider on index cards, the rider now encroaches and covers very little of the front upper edge of the card and it is thus possible to keep the card edge required for the provision of any fastening means, such as for instance the row of perforations 22 in Fig. 4 of the drawings, very narrow.

The application of the invention is by no means limited to rider clips for registers or card indexes. The clip is owing to its extraordinarily firm seat suitable as a uniting or binding member for bodies or articles composed of leaves, sheets or plates. The clip or fastener may thus, for instance, be duplicated as illustrated in Fig. 11, 9, and be employed to unite or join together two leaves or plates of an article along their edges. The improved clip may thus, for instance, be used to attach indicator tags to document files, portfolios or cases. It may also be provided with a hinge 130 at about its middle as shown in Figures 11 and 12 or other articulated connections such as those employed for binding the sheets or leaves in a loose-leaf book or binder. The double fastening device thus constructed 12 comprises the oppositely-arranged clip-elements 211 and 224 on one side of the articulated axis or hinge 130 and on the other side thereof clip-elements 212 and 223. Said clip-elements on either side are respectively provided with prongs 221 and openings 220.

It will be understood that it is not absolutely necessary to punch perforations into the card. It is sometimes ample to emboss depressions or recesses or to secure by other means the firm seating of the leg or limb provided with the said projections in the form of tongues, prongs and the like. The invention is, of course, by no means limited to marking or indicating riders and may equally well serve as a fastening device and as such it fulfills, owing to its peculiar construction, all the conditions with which other fastening devices comply which are secured by rivets, screw bolts and the like.

The fastening device according to the invention may also serve as a carrier or support for cards, for instance, for fixing or mounting them in the back of a book in the manner of leaves. It may, furthermore, be employed as a tag on files or portfolios. The fastening member may 1

be made in duplex form by being provided with hooks, prongs or the like at both ends as described above.

I desire it to be understood that my invention is not limited to the details of construction shown and described by way of example, as various changes and modifications within the ambit of my claims will suggest themselves to those skilled in the art.

10 10 I claim:—

1. In combination with a flat article provided with perforations along one edge thereof, a rider clip comprising two oppositely arranged limbs, means for holding said oppositely arranged limbs against relative displacement, one of said limbs being shorter than the other and comprising at least two portions, the longer of said limbs consisting of a single portion extending across the entire width of said shorter limb, a projection comprising a plurality of claws upon said shorter limb, said claws being presented towards said longer limb, said longer limb being provided with openings suitably located to receive the claws on the shorter limb, said claws being presented through the perforations in said flat article.

2. In a rider clip for flat articles, in combination two oppositely arranged plates, said plates being fastened together midway of their length, the outer ends of said plates on one side being adapted to clasp the edge of a flat article between them, one of said outer ends being provided with a projection comprising inwardly presented claws distributed across the width of the other of said outer ends, the respective outer ends on the other side being provided with windows adapted to receive index strips.

3. A rider clip adapted to be applied to the edge of a flat article, said clip comprising two oppositely arranged flat plates of sheet material fastened together along a fixed axis to form opposed limbs, at least one of said limbs being constructed of resilient material to adapt it to exert a yieldable pressure upon a card having one edge disposed between it and the other of said limbs, one limb being shorter than the other limb and provided with a projection comprising laterally spaced in-

wardly presented claws and in which said longer limb is provided with openings suitably arranged to receive the inwardly presented claws.

4. A rider clip, comprising two oppositely arranged limbs, means for holding said oppositely arranged limbs against relative displacement, one of said limbs being shorter than the other and consisting of at least two portions, the longer limb consisting of a single portion extending substantially in a single plane and across the entire width of the shorter limb with its lower edge offset substantially into the plane of the shorter limb, gripping means extending along the entire width of the lower portion of said shorter limb and presented towards said longer limb, said longer limb constructed to allow the gripping means on said shorter limb to extend below the general plane of the adjacent surface of said longer limb.

5. A rider clip, comprising two oppositely arranged limbs, means for holding said oppositely arranged limbs against relative displacement, one of said limbs being shorter than the other and consisting of at least two portions, the longer limb consisting of a single portion extending across the entire width of the shorter limb, a projection extending along the entire width of the lower portion of said shorter limb and presented towards said longer limb, said longer limb having a longitudinal groove to allow the projection on said shorter limb to extend below the general plane of the adjacent surface of said longer limb.

6. In combination with a flat article, a rider clip comprising two oppositely arranged limbs, means for holding said oppositely arranged limbs against relative displacement, one of said limbs being shorter than the other and comprising at least two portions, the longer of said limbs consisting of a single portion extending across the entire width of said shorter limb, a projection comprising claws upon said shorter limb, said claws being presented towards said longer limb, said longer limb being provided with openings registering with said claws, said claws adapted to press the material of said flat article into the openings in said longer limb.
